UNITED STATES PATENT OFFICE.

PETER G. KLOTZ, OF SANDUSKY, OHIO, ASSIGNOR TO HINDE & DAUCH PAPER COMPANY, OF SANDUSKY, OHIO, A CORPORATION OF OHIO.

MACHINE FOR MANUFACTURING PAPER-BOARD.

No. 1,026,870.

Specification of Letters Patent. Patented May 21, 1912.

Application filed June 11, 1910. Serial No. 566,398.

To all whom it may concern:

Be it known that I, PETER G. KLOTZ, a citizen of the United States of America, residing at Sandusky, in the county of Erie and State of Ohio, have invented certain new and useful Improvements in Machines for Manufacturing Paper-Board, of which the following is a specification, reference being had therein to the accompanying drawings.

The invention relates to apparatus for the manufacture of paper board, more particularly designed for use in manufacture of double faced corrugated paper board.

The invention consists in the means employed for uniting the strips, as more fully hereinafter described.

In the drawings—Figure 1 is a vertical longitudinal section through the machine.

Fig. 2 is a cross section.

In the manufacture of corrugated paper board it is usual to first form the single faced board and in a subsequent operation to apply the second facing strip to the opposite side of the board. The single faced corrugated material is capable of being reeled, but when the second facing strip is attached the board can no longer be bent and must be maintained in substantially the same plane during the subsequent treatment.

The present invention relates more particularly to the means employed for pressing the second facing strip against the corrugated material while the glue is soft and for drying the board during its passage through the machine.

As shown, A is a reel of the single faced corrugated board, from which the strip is fed over rolls B and C to a gluing device D. The arrangement is preferably such that the corrugated side of the strip will face downward and the glue upon the rolls D' is applied to the tips of the corrugations.

E is a reel of plain paper from which the strip is fed over the guide rolls F and G into contact with the glued corrugated strip.

After the facing strip and corrugated strip are brought into contact, they are fed through the drying apparatus. This consists of a hot plate H on which the combined strip rests, together with means for pressing the strip in contact with the plate during its travel thereover. The plate H may be formed of a hollow member supplied with steam, to maintain the proper

temperature. The upper face of this plate extends in the plane of the feed and for sufficient length to insure the proper drying of the material. For holding the material in contact with the hot plate, I preferably employ a series of transversely extending independent presser bars I. These are preferably in the form of rollers which are free to rotate but are limited as to longitudinal movement by pins or stops J. The latter may be secured to the plate and project upward into the path of the end portions J' of the rollers, which are preferably slightly reduced in diameter so as to reduce the friction upon the pin or stop J.

K are strips extending longitudinally of the plate at the ends of the rollers and forming guides therefor.

With the apparatus as thus far described it is evident that the material as it is fed from the plate H, will be held in close contact therewith while the individual rollers or presser bars I, will maintain all portions in equally good contact. If the hot plate is of sufficient length the material may be dried without further apparatus, but where it is desired to accelerate the action or reduce the length of the plate, a drying hood may be employed. As shown L is a hood consisting of an upper plate L' covered with suitable heat insulating material such as M.

N are curtains depending from the plate L' at the sides thereof, extending down to the bed H.

O are heating steam coils arranged beneath the hood above the rolls I. At the forward end of the hood the conduit P is attached, which preferably leads to an exhaust fan (not shown) by which the air and moisture in the hood is constantly removed.

With the construction just described, the heat of the plate H as well as that radiating from the coils O, will expel the moisture from the paper board. The moist air will be removed through the conduit P. There is however, a greater amount of moisture in the hood at the forward end thereof, than at the rear end, due to the fact that the air in exhausting is drawn forward. This is desirable as it prevents the mere surface drying of the paper by maintaining it for a time in a comparatively moist atmosphere, but as the material is fed toward the rear, the amount of moisture in the atmosphere is progressively decreased so as to complete

the drying. The feed of the material through the apparatus may be effected by suitable feed rollers Q at the rear end thereof.

5. What I claim as my invention is:

1. The combination with a hot plate, of means for feeding the material to be dried thereover, a plurality of presser bars for yieldably holding the material in contact 10 with said plate during its movement, the pressure placed upon the material by one presser bar being independent of the remaining bars.

2. The combination with a hot plate, of 15 means for feeding a strip of material to be dried thereover, and a series of transversely-extending presser rollers for holding said strip in contact with said plate.

3. The combination with a hot plate, of 20 means for feeding a strip of material to be dried thereover; a series of transversely extending free presser rollers for holding said strip in contact with said plate, and means for limiting the travel of said rollers.

25. 4. The combination with a hot plate, of means for feeding a strip of material to be dried thereover, a series of transversely extending free rollers resting upon said strip above said plate, and stops at the opposite ends of each roller for limiting the forward movement thereof.

5. The combination with a hot plate, of

means for feeding a strip of material to be dried thereover, a transversely extending roller for holding said strip in contact with 35 said plate said rollers having end portions of reduced diameter, and stops adjacent to the reduced ends of said rollers for limiting the travel thereof.

6. The combination with a hot plate, and 40 means for feeding a strip of material to be dried thereover, of a hood for covering said strip on said plate, and means for withdrawing the moist atmosphere from said hood.

7. The combination with a hot plate, of 45 means for feeding a strip of material to be dried thereover, a hood for covering the strip upon said plate, and means for passing a current of air through said hood from the rear end toward the forward end thereof.

8. The combination with a hot plate, means for feeding a strip of material to be dried thereover, a hood covering said strip comprising a heat insulated top, a curtain 55 at the sides, a heating coil within said hood above said strip, and means for exchanging the atmosphere within said hood.

In testimony whereof I affix my signature in presence of two witnesses.

PETER G. KLOTZ.
